UNITED STATES PATENT OFFICE.

MARCUS O. ANTHONY, OF BARBERTON, OHIO.

ART OF TELEGRAPHY.

SPECIFICATION forming part of Letters Patent No. 783,604, dated February 28, 1905.

Application filed May 10, 1902. Serial No. 106,780.

To all whom it may concern:

Be it known that I, MARCUS O. ANTHONY, a citizen of the United States, residing at Barberton, in the county of Summit and State of Ohio, have invented new and useful Improvements in the Art of Telegraphy, of which the following is a specification.

My invention relates to the general art of telegraphy; and it consists of a novel apparatus for sending and receiving telegraphic signals in which the circuit as commonly understood is dispensed with and one and the same conductor is made the means of transmitting both outgoing and incoming electrical impulses. This conductor may be a wire, a railway-track, or the earth itself, either or in conjunction, no earth insulation being required where a metallic conductor is employed.

The essential characteristic of my invention is the combination with a transmitting-conductor of means for producing telegraphic make-and-break signals in a local battery-circuit and for translating them into corresponding secondary waves or impulses upon and over said conductor and, supplementary thereto, of means for receiving and reconverting the impulses so transmitted into reproductions of the original primary impulses in a second local battery-circuit, including a sounder or other means of making the same intelligible.

The main features of the apparatus in point of novelty are the construction, arrangement, and functions of sending and receiving coils, each having a primary or inner winding and a secondary or outer winding in relatively opposite directions each to each and relatively opposite in the two coils by the arrangement and connection with respect to each other. The primary or inner winding of the receiving-coil is in a battery-circuit including a sending-key and vibrator, while the secondary or inner winding of the receiving-coil has its terminals circuited through a relay controlling an independent battery-circuit containing a sounder. The outer or secondary windings in each case connect at one terminal through a common line to a single main conductor, which, as stated, may be a metallic conductor or the earth, the opposite terminal being "blocked"—i. e., having no electrical connection, (although in the receiving-coil the terminal in question may be connected into the relay-circuit before mentioned.)

The sending and receiving mechanism above outlined, constituting a joint apparatus, is duplicated for each station of a given system and connected in multiple with the main conductor by the service branches common to each apparatus respectively.

The principle involved in sending and receiving over the same conductor may depend upon the rotative direction of the currents in respect to the conductor, the outgoing currents having a relatively opposite rotation to those incoming, the opposite winding of the coils thus adapting them to their respective functions of sending and receiving.

The invention is thus peculiarly adapted to railway service in communicating between stations and moving trains or between moving trains and for use in field operations, such as military campaigns. It also cheapens the construction and maintenance of telegraph-lines and, indeed, is a substitute for the ordinary systems of telegraphy.

My invention is illustrated in the accompanying drawings, in which—

Figure 1 is a diagrammatic view of the system, showing minor circuits and translating instruments, and the branch or service conductors and main conductor as applied in railway service. Fig. 2 is an axial section of the sending and receiving coils to illustrate details.

Referring now to the drawings, A designates the sending and B the receiving apparatus or portions of the general apparatus, respectively, as used upon a railway. Duplicates of the same are located at stations and upon moving trains and connect electrically with the lines of rails of the trackway T as a main conductor.

The sending mechanism A consists of a battery-circuit including a battery or generator a; the primary winding of an induction-coil e, herein termed the "sending-coil;" a telegraphic sending-key b, and a vibrator apparatus P, all connected in circuits traced as follows: from one pole of the battery a

through conductor 2, through sending-key *b*, to post *p* of the vibrator mechanism *P*; thence through make-and-break contact 3 4, vibrator *m*, and line 5, to the primary or inner 5 winding (inner layer) of sending-coil *e*; thence from the opposite terminal of said inner winding (outer layer) back to battery by direct line 1. The magnet-circuit for vibrator apparatus *P* and contacts, beginning at 10 post *p*, is thence through make-and-break contacts 6 and 7 and extended line 10, through magnet-coils *f* and line 8 to conductor 1.

Condenser-shunts are employed for the make-and-break contacts as follows: for contact 15 3 a line 9 connecting across from lines 2 to 5 through condenser *d'*, and for contact 6 a line 10 connecting across from lines 2 to 7 through condenser *d''*.

Upon a suitable base is placed in vertical 20 position a double magnet *f*, and centrally in front of same and in line are erected two vibrating metallic standards *c'* and *m*, the latter being practically an upward extension of the line 5 to contact 4, carried upon said standard, and the former, similarly, a part of line 25 10 to a contact 7, line 10 continuing thence to the upward terminals of magnet-coils *f*. Beyond and in line with standards *c'* and *m* is affixed a metallic post *p*, carrying adjustable 30 contacts 4 and 7, aforesaid, the post being an extension of line 10 at the opposite side of the condenser *d''*. The vibrator *c'* carries also a lateral arm or finger *c*, hooked over and beyond vibrator *m*, breaking contacts 3 4 and 6 35 7. This movement is effected by extending the poles of the double magnet *f* laterally by parallel pole-pieces *f' f''* at the sides of the soft-iron base or head of the arm *c*, as indicated in Fig. 3, producing a solenoidal action 40 or "pull" upon the vibrator *c'* against the natural elasticity of the vibrators.

The sending-coil *e* has its primary winding 45 interposed between the terminals of conductors 1 and 5 of the battery-circuit. Its secondary winding has one blocked terminal—that is, having no electrical outlet—and the other terminal connected to a service-conductor *C*, extending to earth or other natural conductor or to an artificial conductor, such 50 as the track *T* of a line of railway, (as in the present illustration.) These primary and secondary windings are in relatively opposite directions about a permanent magnet-core *x* of hardened steel.

55 The receiving mechanism *B* consists of a coil *e''*, whose primary and secondary windings are relatively in opposite directions and are arranged oppositely to those of coil *e*.

The primary winding of coil *e''* is in a closed 60 circuit 11 12 through a permanent magnet-relay *g*, having a condenser *d'''* interposed in shunt connection 15 between the branches 11 12 of the circuit. The relay *g* operates an outer circuit 13 14 through a local battery *a'* 65 and sounder *k* in the usual manner. The sec-

ondary winding of coil *e''* has a cross connection 16 from the inner terminal of the secondary winding to the line 11 of the primary winding. The coil *e''* is fitted with a core *y* of soft-iron wires bundled.

70 The sending and receiving portions *A* and *B*, above described, constitute a joint apparatus *A B*, which, as already stated, is duplicated at stations and on moving trains and connected to the track or earth in multiple. In trains of cars moving on railways the connection is made through the running-gear and through the wheel-contacts with the rails. Where used in field service—as, for example, in military campaigning—the earth alone may 80 be used as the main conductor through metallic rods driven into the soil or otherwise as temporary connections with the earth.

In permanent railway service the track conduction may be rendered more perfect by 85 bonding the rails, as in electric-railway service; but satisfactory results are obtained for considerable distances where rails are united by ordinary fish-plate joints.

90 Wherever a perfect earth contact can be obtained, (as by metallic rods driven deep enough to reach moist earth, or by buried metallic plates, or by attachment to buried water or gas pipes, &c.,) the earth alone may be utilized as the sole conductor.

95 In the apparatus employed the sending and receiving coils must be substantial duplicates as to windings, but used in reverse one with the other, as indicated in the foregoing description and in the figures of the drawings.

100 As shown in the drawings, the aforesaid coils *e* and *e''* are placed relatively close together end to end. The object of this is to prevent the existence of a magnetic flux of the same polarity, and this is effected by providing each coil with its opposite windings and arranging the primary and secondary windings of one coil relatively opposite to the corresponding winding of the other coil, resulting in current from one coil—say the sending-coil—being largely diverted and sent through the service-conductor to the main conductor whatever the character of the latter.

105 It will be observed that the main conductor (considered as a line connecting two terminal stations) terminates at each end in two branches, each branch terminating in the outer winding layer of an induction-coil. The inner coils in each case connect with the local circuits of the sending-key and receiving-sounder or relay, respectively. I may dispense with a relay and sounder direct where a telephone-receiver is used; but in railway service and the like the separate circuit and relay are preferable. I may also dispense 115 with the vibrator apparatus and condensers in the sending apparatus; but I prefer to employ them as a means of insuring sharper breaks and correspondingly stronger secondary impulses. This method of communication 120 125 130

can be used in building operations and in fire-fighting, &c., in which case a single wire can be embedded in the hose without danger of short-circuiting, as is the case with a two-wire circuit.

5 I claim as my invention and desire to secure by Letters Patent of the United States—

1. The combination in a system of telegraphy of a single main conductor having ungrounded terminals, a transmitting-coil consisting of a single core and inner and outer layers or windings arranged in relatively opposite directions, and a battery-circuit including a sending mechanism and the inner or primary winding of the said coil, the said outer or secondary of the coil having one terminal open and the opposite terminal connecting with the said main conductor.

2. The combination in a system of telegraphy, of a single track-rail forming a main conductor, a transmitting-coil consisting of a single core and inner and outer layers or windings arranged in relatively opposite directions, and a battery-circuit including a sending apparatus and the inner or primary winding of the transmitting-coil, the said outer or secondary of the coil having one terminal open and the opposite terminal connecting by a service-conductor with the said track-rail.

3. The combination in a system of telegraphy, of a single conductor having ungrounded terminals, transmitting and receiving coils each having one end open said coils each including a single core and inner and outer layers or windings arranged in each coil, in relatively opposite directions, a battery-circuit comprising a sending apparatus and the inner or primary winding of the transmitting-coil, a relay through which the terminals of

the inner or secondary winding of the receiving-coil is circuited, and an independent battery-circuit containing a sounder, and controlled by the relay, said outer layer or winding of the said coils connecting through a common line to said main conductor.

45

4. The combination in a system of telegraphy of a single main conductor having ungrounded terminals, transmitting and receiving apparatus and circuit connection therefor, transmitting and receiving coils each consisting of a single core and inner and outer layers wound in opposite directions relative to each other, and the said windings of the receiving-coil arranged opposite to those of the transmitting-coil, and a service-conductor leading 50 to the main conductor and to which one terminal of each of the outer or secondary layer of the sending and receiving coils is connected.

5. In a system of telegraphic communication, the combination of a single main conductor having ungrounded terminals, in combination with complementary sending and receiving apparatus and two induction-coils each comprising inner and outer winding arranged in opposite directions relative to each other 65 and with the winding of the respective layers in the sending-coil arranged opposite to the winding of the same layers in the receiving-coil, said terminals of the main conductor constituting the outer or secondary winding 70 of the coils.

In testimony whereof I have hereunto set my hand in presence of two subscribing witnesses.
